UNITED STATES PATENT OFFICE.

DIXON S. CARTER, OF BLOOMINGTON, ILLINOIS.

PULVERIZER.

1,333,159.

Specification of Letters Patent. Patented Mar. 9, 1920.

Application filed February 26, 1917. Serial No. 151,112.

To all whom it may concern:

Be it known that I, DIXON S. CARTER, a citizen of the United States, residing at Bloomington, in the county of McLean and 5 State of Illinois, have invented a certain new and useful Improvement in Pulverizers, of which the following is a specification.

My invention has for its object to provide new and improved means for fastening pulverizer blades to a mold board. One object 10 is to provide a unit assembly whereby a number of pulverizer blades may be positioned about the outer edge of the mold board where they will do their pulverizing 15 work with a maximum of efficiency and a minimum of difficulty. Another object is to provide means whereby the blade may be adjusted about the mold board at the will of the operator and to provide means whereby 20 the blades may be previously assembled as a unit and then positioned on the mold board without the possibility of any change in position by them during operation. Another object is to provide a light and flexible 25 and adjustable means for attaching such pulverizer blades without interfering with the operation of the plow and without interfering with the functioning of the plow in any way.

30 My invention is illustrated more or less diagrammatically in the accompanying drawing, wherein—

Figure 1 shows a perspective view of the mold board with other plow parts omitted. 35 Fig. 2 shows a side elevation of the adjusting plate with cutting blades attached, the mold board position being indicated in dotted lines.

Fig. 3 shows a section along the line 3—3 40 of Fig. 2.

Fig. 4 a plan elevation of one of the knives with attaching member.

Fig. 5 is a section along the line 5—5 of 45 Fig. 3.

Like parts are indicated by like letters in all the figures.

A is a plow share. On it is mounted the usual form of mold board A¹. This mold board is supported by a brace A², held in 50 position thereon by a bolt A³ having its head flush with the working surface of the mold board and clamped in position by the nut A⁴.

B is an adjusting and assembly plate. It 55 is made of relatively thin and flexible sheet metal. It is provided along its upper edge

with a series of perforations B¹ arranged in groups of two at predetermined intervals. It is tapered at its rear end as shown at B² and provided with a series of perforations 60 B³, arranged some of them concentrically about a central perforation B⁴, the distance between the different holes along a radial line being substantially equal to the distance between the groups B¹. The lower forward 65 portion of the plate is provided with a series of closely spaced perforations B⁵.

C, C¹ and C² are pulverizing knives of curved or similar shape as shown in Fig. 3, and having a gradually tapering cutting 70 edge as shown in Fig. 5. These knives are each fastened to a knife handle C³, which handle is bent up about the end of the knife and riveted therethrough as shown in Figs. 2 and 3. These knife handles are perforated 75 as at C⁴, the perforations being arranged radially about the central forward perforation C⁵, the distance between perforations on the radial line being substantially the same as the distance between the perforation groups B¹ or between the perforations grouped about the central perforation B⁴. This handle C³ is for the major portion of 80 its length flat, being only curved away immediately adjacent the knife.

Attention is called to the fact that the knife immediately adjacent the point where it connects to the knife handle is cut away or slotted as at D and this slot is so arranged that when the parts are in position 90 the knife slot engages the edge of the mold board and the cutting edge of the knife commences a little inside the periphery of the mold board, while the handle is located 95 entirely behind the mold board, so that the handle and all handle attaching and controlling parts are always located out of the line of movement of the furrow slice as it passes across the mold board.

It will be noted that the handles themselves are flat as shown, to conform with the main base plate and that they are bolted to the plate, the handle being bolted by two or more bolts as the case may be. The bolts pass through the holes B¹, B³ and hold 100 the knife handles on the plate, it being understood that the assembly by slight changes in relative position of parts may be adjusted for right and left hand plows, as the case may be. The bolt heads will preferably in 105 either event be located between the plate and the mold board and it makes little if any 110

difference on which side of the plate the handles are located.

It will be evident that while I have shown in my drawings an operative device, still many changes may be made both in size, shape and arrangement of parts without departing materially from the spirit of my invention, and I wish, therefore, that my drawings be regarded as in a sense dia-
10 grammatic.

The use and operation of my invention are as follows:—

The farmer or other user wishing to apply my device to the mold board of his plow, takes the separate knives with their handles and bolts them one at a time upon the base plate changing their position both angular and bodily with respect to the plate until he obtains that general location of the 15 different knives which appears to most nearly suit his particular plowing circumstances. He then releases the bolt which holds the mold board on the brace, he draws it out and positions the plate between the 20 mold board and the brace in such wise that the knives assume the position shown in Fig. 1, arranging the parts such that each slot and each knife closely engages the edge of the mold board. This can be done with 25 a very slight limit of adjustment, and the plate is so positioned that the bolt which passes through the mold board may pass through it and then through the brace. The farmer, after the parts are in position 30 tightens the bolts and nut, to clamp the parts together, and in this situation the plate assists in holding the plate and the knives rigidly and firmly in position. There being a certain amount of flexibility and 35 elasticity to both the plate and the knives it is obvious that there will be a slight ten-
40

sion on the plate, and this tension tends to clamp or lock the knives firmly in position and of course since the slots in the knives closely engage the mold board, there 45 is no tendency for the plate to be bent away from the mold board, and it will conform more or less closely to the curvature thereof. Thus the whole knife assembly may be attached and detached as a unit to the mold board, and any individual knife may be attached and detached or any individual knife or the whole assembly as a unit may be adjusted with respect thereto.
50

I claim:

1. The combination of a plow mold board with a series of blades slotted to engage its edge and a common support for them, adapted to be adjustably secured on the back of and entirely within the edge of the mold 60 board, each blade adjustable as to its position about the rear edge of the board and as to its angle with reference to the furrow strip and each projecting upwardly into the path of the furrow strip and extending 65 substantially in rear of the rear edge of the mold board.

2. The combination of a plow mold board with a series of blades slotted to engage its 70 edge, and a common support for the blades, adapted to hold them in position about the edge of the mold board, said common support adapted to be secured on the back of and entirely within the edge of the mold board.
75

In testimony whereof I affix my signature, in the presence of two witnesses, this thirteenth day of February, 1917.

DIXON S. CARTER.
